Clement L. Carter

UNITED STATES PATENT OFFICE.

CLEMENT L. CARTER, OF UNION CITY, INDIANA.

POST-HOLE DIGGER.

SPECIFICATION forming part of Letters Patent No. 283,753, dated August 28, 1883.

Application filed July 5, 1883. (No model.)

To all whom it may concern:

Be it known that I, CLEMENT L. CARTER, of Union City, in the county of Randolph and State of Indiana, have invented certain new and useful Improvements in Post-Hole Diggers; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved post-hole digger or earth-auger. Fig. 2 is a sectional view of the same. Fig. 3 is a view of my auger-blade with my secondary blade attached.

Similar letters of reference indicate corresponding parts in each figure.

My invention has relation to post-hole diggers; and it consists in the improved construction and combination of parts of a post-hole digger having two concavo-convex blades and two secondary blades. The concavo-convex blades are secured rigidly to the lower end of two bars hinged together, and each bent sideward to form the handles, and having means for holding them adjustably together, as hereinafter more fully described and claimed.

In the accompanying drawings, the letters A A indicate the two cutting-blades, which are concavo-convex, and their cutting-edge H is perpendicular, excepting about two inches of the lower end, S, is cut at an angle of forty-five degrees with the perpendicular cutting-edge H. The blades A A are rigidly connected to the lower ends of the two bars C C, which are bent a short distance above the cutting-blades A A, so as to be parallel one upon the other, with their flat surfaces together, and are hinged at f. The upper ends of the bars C C are bent sideward to form the handles D D. The notched bar F is hinged to one of the bars C under the handle at d. The object of the notched bar F is to engage by means of the notches with the lug e to hold the bars C rigidly in position. The lever E, being pivoted

to the notched bar F at b, and resting on the lug e, forms a combination by means of which the operator, by lifting the lever E, disengages 50 the notched bar F, when the auger can be opened or closed at will.

In the construction of my improved post-auger blades for an ordinary-sized auger, I cut the steel ten inches long and five inches 55 wide. The upper cutting-edge, H, is left straight eight inches; the lower two inches. S is cut at an angle of forty-five degrees with the cutting-edge H. The opposite lower edge, O, is slightly rounded or pointed. The edges 60 H S O, Fig. 3, are sharpened for cutting purposes. The blades are then bent or curved to correspond with the sized hole the auger is intended to cut.

My attachment or secondary blade is not intended for boring purposes, but only for reaming after the hole is made. It is made of steel, about eight inches long and three inches wide, with straps of iron or other metal riveted near one edge. These straps are bent at each end, 70 as seen at a a, Fig. 2, so as to fit the primary auger-blades. When the auger will not make a hole as large as desired, one of the secondary blades, as seen at B, Fig. 1, and the detached blade, Fig. 3, is attached to each of the 75 auger-blades. The hole can then be reamed to almost any size desired, making a valuable attachment for setting telegraph-poles.

Having thus described my invention, I claim as new and desire to secure by Letters Patent 80 of the United States—

1. The secondary blades B, in combination with the primary blades A A, as and for the purposes set forth.

2. The lever E, in combination with the 85 notched bar F and the lug e, as and for the purposes set forth.

In testimony that I claim the foregoing as my own I have hereunto affixed my signature in presence of two witnesses.

CLEMENT L. CARTER. [L. S.]
